CLAIM

The ornamental design for a fence assembly, as shown and described.

DESCRIPTION

FIG. 1 is a front perspective view of the fence assembly with the front and rear rails shown, and the table shown in hidden lines;

FIG. 2 is a rear perspective view of the fence assembly of FIG. 1 with the front and rear rails shown, and the table shown in hidden lines;

FIG. 3 is a top view of the fence assembly shown in FIG. 1; FIG. 4 is a front view of the fence assembly shown in FIG. 1; and,

FIG. 5 is a side view of the fence assembly shown in FIG. 1. The other side of the fence assembly shown in FIG. 1 is symmetrical.

The bottom of the fence assembly shown in FIG. 1 is plain and unornamented.
